SHEAVE BLOCK CONSTRUCTION

Louis M. Regan, Redondo Beach, Calif., assignor to Regan Forge and Engineering Company, San Pedro, Calif., a corporation of California

Application November 25, 1955, Serial No. 548,916

7 Claims. (Cl. 254—192)

This invention relates to blocks of the traveling block and crown block type carrying a plurality of sheaves, such as are commonly employed with heavy equipment characteristically found especially in oil fields.

A particular object of the invention is to provide a sheave block structure wherein a strong, durable sheave arrangement is provided that overcomes load deflection of conventional pin or shaft arrangements upon which sheaves are commonly mounted.

Another object of the invention is to provide a compact and narrow sheave block structure of the indicated nature in which all sheaves are arranged about a common axis but without a common deflectable axle.

A still further object of the invention is to present a sheave block structure which permits manufacture with ordinary shop tolerances, and without the necessity for special fitting when assembling, variations in overall length of the sheave assembly being easily cared for by moderately simple adjustments which do not in any way affect the strength and efficiency of the sheave assembly.

Another object is to provide a structure of the indicated nature which is sufficiently simple to permit replacement of worn or broken parts in the field, without the necessity for long shut-down and transporting the blocks to a shop.

It is an associated object to provide such a simple sheave block structure that, when replacing parts in the field, necessary working adjustments are easily made, it being also an object to provide such structures which are relatively inexpensive to manufacture, even where relatively large numbers of sheaves, for example six or seven or more sheaves, are employed in a horizontal series.

The invention also has as an object the employment of a plurality of load-receiving support members, some of which intervene between sheaves of the assembly, whereby to transmit loads directly to said support members at positions intermediate the ends of the sheave assembly, it being also an object to provide a supporting head or load-carrying structure for the assembly which has direct supporting connection with such intervening support members. A further object is to provide annular bearings within such support members (which may be in the form of plates) to provide bearings for oppositely extending hubs of interposed sheaves, it being also an object to distribute the load from any given sheave to two such support members at the opposite sides of such sheave.

Other objects of the invention, and various features of construction thereof, will be apparent to those skilled in this art upon reference to the following specification and the accompanying drawings in which:

Fig. 1 is a side elevation of a traveling block constructed in accordance with the present invention;

Fig. 2 is a transverse longitudinal section taken on the line 2—2 of Fig. 4;

Fig. 3 is a top plan view as indicated by the line 3—3 of Fig. 2;

Fig. 4 is principally a vertical cross sectional view taken as indicated by the line 4—4 of Fig. 2;

Fig. 5 is a fragmentary sectional detail on an enlarged

2

scale indicating the mounting at one end of the transverse supporting cross shafts extending through the assembly;

Fig. 6 is a fragmentary vertical cross section on an enlarged scale showing roller bearing mountings for the sheaves about the axis of the assembly and showing ball thrust bearings for the sheaves also arranged about the axis of the assembly, as indicated by the lines 6—6 of Figs. 1 and 2;

Fig. 7 is partially a vertical cross section through the axis of the assembly as indicated by the line 7—7 of Fig. 2;

Fig. 8 is a side elevation of the general assembly of this invention modified to adapt it to a crown block structure;

Fig. 9 is in part a fragmentary cross section through the axis of the structure as indicated by the line 9—9 of Fig. 8 and in part a corresponding front elevation of the structure of Fig. 8.

Having reference particularly to Figs. 2, 4 and 6 to 9, the dominating elements of the sheave block structure of this invention, whether a traveling block as in Figs. 1 to 7, or a crown block as in Figs. 8 and 9, or the like, include

horizontal series of pulleys or sheaves 10 provided with the usual pulley grooves, and a series of intervening supporting beams or load-receiving plates 12 on which the sheaves 10 are borne through the medium of central hubs 14 of the sheaves, portions of such hubs extending laterally within and in supporting engagement with annular series of roller bearings 15 which are in turn disposed within central openings in the beam plates 12, there being a roller bearing series 15 for each hub 14 of each sheave in each beam plate 12. The beam plates 12 are in turn carried on suitable peripherally arranged supports beyond the sheaves 10. In the traveling block assembly, these supports are in the form of cross bolts or pins or shafts 16 (Figs. 2 and 4) extending through

integral mounting lugs 18 at the corners of the beam plates 12. In the crown block structure of Figs. 8 and 9 the direct support for beam plates 12a, instead of being cross shafts 16a, are I-beams 20 upon which rest lateral horizontally extending ends of the beam plates 12a. As best indicated in Fig. 7, the beam plates 12 are thickened annularly at 12b around their central openings to provide sufficient thickness for two roller bearing assemblies 15 for adjacent sheaves, as above described, whereas their peripheral portions are relatively thin so as to be cleared by peripheral groove elements 22 of the sheaves 10.

A thrust tube 24, containing small grease tubes 24a leading to the sheaves, is axially positioned within the sheave and beam plate assembly but the tube 24 does not provide a bearing for any of the sheaves although clearance may be small as indicated in Fig. 6. The thrust tube 24 has both of its ends threaded at 25, these threaded ends receiving thereon threaded plate-like caps 26 which are in turn received in countersunk seats 27 in the end beam plates 12.

As best illustrated in Fig. 6, the hubs 14 of the sheaves 10 oppose each other in the main portion of the assembly, the outer hubs 14 of the outermost sheaves 10, however, opposing the caps 26. In order properly to space the various pairs of hubs 14 from each other and the outer hubs 14 from the caps 26, annular series of ball thrust bearings 28, these including suitable ball races, are used as shown. Since the caps 26 are adjustable, observance of precision tolerances in the manufacture of the sheaves 10 and their hubs 14 and of the beam plates 12 is unnecessary, thus greatly minimizing cost of manufacture and simplifying installation. When the caps 26 are threaded adjusted on the ends of the thrust tube 24 to meet the spacing requirements of the sheaves 10 and the intervening ball thrust bearings 28, the caps

26 are anchored in position on the end beam plates 12 by means of annular series of threaded nut-like bushings 30 which are screwed into peripheral corresponding threaded holes 31 in the caps 26 so as to bear at their inner ends against the adjacent seat portions 27 of the outer beam plates 12. The nut-like bushings 30 are countersunk at 32 as best illustrated in Fig. 6 and receive the heads of cap screws 33 which pass through the bottom walls 34 of the bushings 30 and are threaded into threaded seats 35 in the end plates 12.

By the adjustment means at 25 and the adjustment means 30 which are locked in position by the cap screws 33, variations in the longitudinal dimensions of the assembly of sheaves 10 and beam plates 12 are easily accommodated. Also these adjustments make it possible to shift the entire assemblage of sheaves 10 in intervening beam plates 12 and with respect to the end beam plates 12.

The entire assembly of sheaves 10, beam plates 12, caps 26 and thrust tube 24 of the traveling block of Figs. 1 to 7 is adapted to be picked up when necessary 20 and suspended through a top head 40 seen in Figs. 1 to 4 and 7 which is provided with a suspension clevis 42 (Fig. 2) at its top and with a series of depending lugs 44 which depend between and serve as spacers for the mounting lugs 18 provided at the upper corners of the beam plates 12, all of these lugs 18 and 44 receiving the cross-tie shafts 16 which bind the assembly of sheaves 10 and plates 12 together in a rigid operative unit, once the proper adjustment has been attained through the adjustment means 25 and 30 as described above. The 30 anchoring of the ends of the shafts 16 is illustrated in the enlarged detail of Fig. 5 which shows a nut 45 threaded snugly onto the end of the respective shaft 16, such nut 45 being received in a countersunk seat 46 in the respective end beam plate 12 and anchored against rotation by a rock screw 47 entering one of a series of holes 48 in the nut 45 and being threaded into a corresponding threaded seat 49 in the beam plate 12.

A comparable supporting or suspending structure is found at the bottom of the sheave and beam assembly, 40 this being in the form of a depending tapered head 50 this being in the form of a depending tapered head 50 having a plurality of upstanding lugs 54 disposed between and spacing the lower lugs 18 of the beam plates 12, all of these lugs 18 and 54 receiving the respective cross-tie bolts 16, whose ends are anchored in the end beam plates 12 as shown and described in connection with Fig. 5.

Respecting some of the details of construction shown in the enlarged fragmentary view of Fig. 6, in addition to the adjusting means previously described whereby the caps 26 and the thrust tube 24 are connected to the end or side beam plates 12, it is to be noted that the roller bearing series 15 are arranged in pairs, except for those co-operating with the side or end beam plates 12, so that, as previously indicated, the roller bearing series for the opposing hubs 14 of each of two adjacent sheaves 10 are carried by the same intervening plate 12, and as a result of this arrangement the load transmitted by each sheave 10 is divided so as to be passed to two different beam plates 12, each intervening plate 12 taking half the load from each of two sheaves 10. As illustrated in Fig. 6, each roller bearing series 15 include an outer bearing ring 60 which is annularly shouldered at each side as indicated at 61 to provide bearings for the opposite ends of the rollers 62. Also, as in the form shown, adjacent outer rings 60 may be in contact with each other at their inner edges. Each roller bearing series 15 also includes an inner bearing ring 64 which is borne upon the radially outward directed bearing face 65 of the respective sheave hub 14. The outer edge of each inner bearing ring 64 bears against a lateral shoulder 66 at the juncture of the hub 14 with the corresponding side wall of the web of the respective sheave 10. Each series of

rollers 62 is positioned by the usual bearing retainer cage 68. By these means the members of each pair of outer bearing rings or races 60 are contiguously disposed in press fitted condition in their seats in the central opening of the respective beam plate 12, and adjacent inner bearing rings or races 64 are out of contact with each other, being press fitted against their lateral seats 66. The relationship of the beam plates 12 and their bearing rings or races 60 is further maintained by reason of the previously described spacing function of the lugs 44 of the top head 40 (Fig. 4) and the lugs 54 of the bottom head 50 which fit between the beam plate lugs 18, all of which lugs receive the cross-tie shafts 16.

With respect to the ball thrust bearings 28 between opposing hubs 14 and between the caps 26 and the outer hubs 14, these include typical annular bearing rings or races 70, intervening balls 72 and retainer cages 74, these units being mounted, as by press fitting, into annular seats 75 in the respective hubs 14. With the bushings 30 and lock screws 33 in the caps 26 loosened or removed, adjustment of the caps 26 on the thrust tube 24 is easily accomplished. For shift of the sheaves 10 in relation to the plates 12 as may be required, and to adjust properly the various ball bearings 28, the threaded bushings 30 are turned down in their threaded openings 31 with their back walls 34 bearing against the seats 27 in the end plates 12. Positioning of the lock screws 33 in the positions shown in Fig. 6 binds all of the parts in their adjusted positions. By such means, replacement sheaves 10 and beam plates 12 may be constructed with much wider tolerances than is permissible where structures must be produced with only precision tolerances. As a consequence, replacements may be made in the field without the necessity of transporting the entire sheave block to a shop, as is commonly done. Also, by this arrangement, the entire assembly of sheaves 10 with their thrust bearings 28 may be shifted axially when necessary, as for the purpose of preventing contact of the sheave groove elements 22 with the beam plates 12.

As also seen in Fig. 6, grease tubes 24a are positioned within the thrust tube 24, as by means of head plates 75, appropriate fittings 76 leading to grease chambers 77 within the respective hub and roller thrust bearing assemblies, there being a tube 24a for each bearing 15, 45 28. Introduced grease will pass the ball bearings 28 to supply the roller bearing series 15, appropriate grease seals being used, such as laterally projecting rings on the webs of the sheaves 10 and corresponding annular seats in the adjacent bearing rings 60 as indicated at 78.

When a sheave block of this improvement is assembled, including the top head 40 and the bottom head 50, the edges of the sheaves are covered by any type of curved protecting plates 80 mounted in any appropriate manner, as by pins 81 (Fig. 2), and provided at their upper ends with slots 82 to pass the usual wire lines carried in sheave grooves 22.

In Figs. 8 and 9 there is illustrated the previously mentioned modification of the sheave block of this invention for crown blocks. Here the sheaves 10 are arranged in alternating relation with beam plates 12a whose end portions project to the opposite sides of the sheaves sufficiently to rest upon the mentioned I-beams 20 at the top of an oil well derrick. As seen in Fig. 9, the beam plate structures 12a may be built up instead 65 of cast, a thin middle member 12a extending outward between the sheave groove elements, thickened sections 85, lying within the sheave groove elements, being appropriately connected to the middle elements 12a to provide the wide seat at each central opening to accommodate the two roller bearing series 15. Beyond the sheaves 10 spacers indicated at 86 are used to position the plates 12a at the plate ends, the cross shafts 16a passing therethrough and maintaining the relationships. In practice, these spacers are conveniently thickened ends 70 75 of the plates 12a.

The described constructions provide for horizontal alignment of the axes of the sheaves 10 and intervening beam plates in closely assembled relation, the entire assembly being readily adjusted through the medium of the caps 26 and associated adjusting means for properly positioning the sheaves along such axes and properly adjusting the thrust bearings 28, the loads on the various sheaves being borne by the adjacent beam plates 12 or 12a, thereby avoiding bending stresses which create distortion due to load deflection in sheave blocks where the sheaves are borne upon a common center pin or shaft whose ends are directly connected to main supporting means. Also, by the present constructions short over-all length is obtained and complete interchangeability of sheaves and beam plates with wide machining tolerances is possible. In the latter respect, stock parts can thus be changed in the field and replaced. The described adjustment through the caps 26 provides ready unit adjustment of the sheave assembly, especially with respect to the intervening beam plates whereby to offset rubbing or touching of the sheave groove elements with the beam plates.

In the case of the traveling block the combined load on the assembled sheaves is transmitted continuously and evenly throughout the width of the block structure through the load-receiving cross shafts 16 and the lower suspension head 50 by way of its lugs 54 mounted on the shafts 16.

Thus, loads during operation are concentrated only at the bottom head clevis 52 which is readily cast to withstand such loads and does not impart load distortion or deflection to cross shafts or pins supporting the sheaves.

I claim as my invention:

1. In a sheave block construction, the combination of: end and intermediate plates arranged in axially spaced relation and respectively provided with axially aligned openings; sheaves interleaved with said plates and each provided with two axially extending, tubular hubs respectively projecting from opposite sides thereof, 40 said opening in each of said end plates having disposed therein the adjacent one of said hubs of the adjacent one of said sheaves, and said opening in each of said intermediate plates having disposed therein in opposed end-to-end relation the adjacent pair of said hubs of the 45 adjacent pair of said sheaves; journal bearings in said

openings and respectively engaging said hubs therein to rotatably support said sheaves; intermediate thrust bearing means engaging said hubs which are within said opening in each of said intermediate plates for axially spacing apart the adjacent pair of said sheaves; end thrust bearings respectively engaging said hubs which are within said openings in said end plates; axial tie means extending through said hubs and adjustably engaging said end thrust bearings and said end plates, there being a radial running clearance between said axial tie means and said hubs; and other tie means located radially outwardly of said sheaves and extending through each of said intermediate plates and connected to said end plates.

2. A sheave block construction as set forth in claim 15 1 wherein said axial tie means includes a tubular tie member within said hubs.

3. A sheave block construction as set forth in claim 1 20 wherein said axial tie means includes a tie member within said hubs and end caps adjustably connected to said tie member and seated against said end thrust bearings and said end plates.

4. A sheave block construction according to claim 3 including means for locking said end caps to said end plates.

5. A sheave block construction as defined in claim 3 including adjusting elements respectively threaded connected to said end caps and respectively seated on said end plates.

6. A sheave block construction according to claim 5 30 including means for locking said end caps and said end plates together.

7. A sheave block construction according to claim 5 including means for locking said end caps and said end plates together, said locking means including screws extending through said adjusting elements and threaded into said end plates.
